UNITED STATES PATENT OFFICE.

UTLEY WEDGE, OF ARDMORE, PENNSYLVANIA.

PUMP FOR CORROSIVE FLUIDS.

1,027,947.

Specification of Letters Patent.

Patented May 28, 1912.

Application filed September 13, 1911. Serial No. 649,184.

To all whom it may concern:

Be it known that I, UTLEY WEDGE, a citizen of the United States, residing in Ardmore, Pennsylvania, have invented certain

5 Improvements in Pumps for Corrosive Fluids, of which the following is a specification.

My invention relates to that class of pumps which are used for pumping corrosive fluids such, for instance, as sulfuric acid or other corrosive fluid or gas. The ordinary pump, whether of the centrifugal or reciprocating type, when used for such purpose, is subject to the disability that the corrosive action of the fluid which is being pumped rapidly impairs or destroys the material employed for packing the driving shaft, if the pump is of the centrifugal type, or for packing the piston rod, if the pump is 20 of the reciprocating type.

The object of my invention is to prevent such destructive or deteriorating effect upon the packing, and this object I attain by interposing, between the stuffing box or other 25 packing carrier of the pump and the body of corrosive fluid within the pump, a body of non-corrosive fluid which will prevent access of said corrosive fluid to the packing material. By preference, the non-corrosive 30 fluid which is thus employed is of a lubricating character.

In the accompanying drawings—Figure 1 represents, partly in elevation and partly in vertical section, a rotary or centrifugal 35 pump constructed in accordance with my invention, and Fig. 2 is a similar view of a reciprocating pump embodying the invention.

In Fig. 1 of the drawing, 1 represents the 40 casing of the pump which has a central inlet 2 at the bottom and a peripheral outlet or discharge 3, the usual vaned drum of such pump being rotated by means of an electric or other suitable form of motor 4, 45 through the medium of a shaft 5. This shaft passes through a stuffing box 6 mounted at the top of a tubular casing 7 interposed between the stuffing box and the pump casing 1, the interior of this casing 7 being 50 in communication with the pump chamber so that a column of the corrosive fluid which is being pumped will rise in the casing 7 around the shaft 5, the height of this column being dependent upon the pressure to which 55 the discharge from the pump is subjected and the top of the column being always some

distance below the stuffing box 6, its level being, by preference, indicated by means of an external gage glass 9, or other suitable indicator on the casing 7.

Between the top of the column of corrosive fluid and the stuffing box 6 is maintained, in the space 10 surrounding the shaft 5, a body of air, oil, or other non-corrosive fluid of lesser specific gravity than the corrosive fluid which is being pumped, this body of non-corrosive fluid being under such pressure as to maintain the desired level of said column, and being supplied to the space 10 through a suitable pipe 11, which may be provided with a valve 12 for admitting fresh supplies to compensate for any loss by leakage or other waste, or this valve may be an automatic regulating valve for maintaining a constant pressure within the space 10. If the non-corrosive body is of a liquid character and incompressible it will simply be necessary to replenish it at intervals as indicated by the rise of the level of corrosive fluid in the gage glass 9. The interposition 80 of this body of non-corrosive fluid between the corrosive fluid and the packing material in the stuffing box effectually prevents any access of such corrosive fluid to said packing material and any destructive or deteriorating effect upon the latter. By preference, the interposed body of fluid consists of oil or other material which will have a lubricating effect upon the packing as well as the isolating effect for which it is mainly 85 intended.

In Fig. 2 I have illustrated the application of my invention to a reciprocating pump having suitable valved intakes 2^a, valved outlets 3^a, piston 13 and piston rod 95 5^a, the latter operating within the tubular casing 7 which is provided, as before, with the gage glass 9, valved fluid inlet pipe 11 and stuffing box 6.

I claim:

1. The combination, in a pump for corrosive fluid, of the pump casing, the packed operating member of the pump, and a tubular casing projecting from the pump casing, said tubular casing containing the operating member of the pump and carrying the packing therefor, and in communication with the pumping chamber whereby it may also contain a column of the corrosive fluid, and a body of non-corrosive fluid interposed between said column and the packing material.

2. The combination, in a pump for corrosive fluid, of the pump casing, the packed operating member of the pump, and a tubular casing projecting from the pump casing, said tubular casing containing the operating member of the pump and carrying the packing therefor, and in communication with the pumping chamber whereby it may also contain a column of the corrosive fluid, and a body of fluid lubricant inter-

posed between said column and the packing material.

In testimony whereof, I have signed my name to this specification, in the presence of two subscribing witnesses.

UTLEY WEDGE.
